Frank D. Werner, Minneapolis, Ralph M. Darr, Excelsior,
George F. Nado, St. Paul, and Paul S. Petersen, Minne-
tonka, Minn., assignors to Rosemount Engineering
Company, Minneapolis, Minn., a corporation of Minne-
sota

Filed Mar. 31, 1965, Ser. No. 84,534

Term of patent 14 years

(Cl. D7—7)

FIG. 5

FIG. 8

FIG. 1 is a front perspective view of a combined ski boot and shroud embodying our new design;

FIG. 2 is a rear perspective view thereof;

FIG. 3 is a side elevational view thereof;

FIG. 4 is a top plan view thereof;

FIG. 5 is a side elevational view of the side opposite that shown in FIG. 3;

FIG. 6 is a bottom plan view thereof;

FIG. 7 is a front elevational view thereof; and

FIG. 8 is a rear elevational view thereof;

We claim:

The ornamental design for a combined ski boot and shroud as shown.
